HOLDER FOR SPOOLS OF WRAPPING CORD

Jack G. Inman, Carrollton, Ill.

Application December 6, 1951, Serial No. 260,135

7 Claims. (Cl. 242—142)

1

This invention relates generally to holders for wrapping cord and more specifically to such a device which is adapted for use in association with a counter, or other support, on which packages are wrapped, the predominant object of the invention being to provide such a holder for spools of wrapping cord that may be secured to the counter or other support with which it is associated in such manner that the spool of cord is disposed out of sight beneath the counter, or other support, and with only an ornate cord dispensing portion appearing above the counter, or other support.

Fig. 1 is a side elevational view illustrating one of the holders for spools of wrapping cord of the present invention, a portion of an element by which the holder is supported being shown in Fig. 1.

Fig. 2 is an enlarged vertical section taken on line 2—2 of Fig. 1.

Fig. 3 is an enlarged fragmentary section taken on line 3—3 of Fig. 2.

Fig. 4 is an enlarged fragmentary section taken on line 4—4 of Fig. 2.

Fig. 5 is an enlarged horizontal section taken on line 5—5 of Fig. 2.

In the drawing, wherein is shown for purposes of illustration, merely, one embodiment of the invention, A designates generally the improved holder for spools of wrapping cord of this invention. The holder A includes a tubular member 1, the upper portion of which is extended through an opening B' formed through a counter B, or other supporting structure. At the lower end thereof the tubular member 1 has a pair of opposed inverted L-shaped slots 2 formed therein, each of said slots having a vertical portion 2a which is open at the bottom edge of the tubular member 1 and a portion 2b which extends horizontally for the upper end of said vertical slot portion and circumferentially of the tubular member 1. Also, the lower portion of said tubular member 1 has mounted thereon a tubular cap 3 which is provided with an annular flange 3' at its top, said cap being provided with a pair of opposed protuberances 4 which extend inwardly from the inner face of a lower portion of the circumferential wall of said cap. The cap 3 is applied to the lower portion of the tubular member 1 by moving said cap upwardly on the lower portion of said tubular member in such position that the protuberances 4 will move upwardly of the vertical portions of the slots 2 and thereafter rotating the cap so that said protuberances will be disposed in the horizontal portions of the slots, and thus will retain the cap in a mounted position on the lower portion of the tubular member 1. The tubular member 1 has mounted thereon a collar 5 which serves a purpose to be hereinafter set forth.

The holder A includes also a head 6 which is provided with a cavity 7 that receives the upper portion of the tubular member 1, as is shown to

2

good advantage in Fig. 2, the head 6 and the upper portion of the tubular member 1 being cemented, or otherwise secured together. The bottom face of the head 6 rests on the top face of the counter B or other supporting structure, and said head has formed therein a curved cord passageway 8 which communicates at its lower end with the passageway through the tubular member 1, and its opposite end is open at a face 6' of the head 6. At the side of the head 6 opposite to the side thereof at which the curved cord passageway 8 is open at the face 6', said head is provided with a slot 9 that receives a blade 10, said blade having a cutting portion a part 10' of which projects outwardly beyond a portion of the head 6 (see Fig. 2). Also, the head 6 is provided with a groove 11 that is located immediately adjacent to the open end of the cord passageway at the face 6' of said head. As is shown to good advantage in Fig. 4 the groove 11 is provided with an inclined bottom wall 11' and said groove is of such width that cord which is supported by the holder A when pulled into the groove will be clamped and held therein, this being for a purpose that will be hereinafter explained.

When it is desired to apply a spool S of wrapping cord to the cord holder A the cap 3 is rotated in the appropriate direction to bring the protuberances 4 of said cap in alignment with the vertical portions 2a of the slots 2, and the cap is moved downwardly, the protuberances 4 or the cap moving downwardly through said vertical portions of said slots. The cap 3 being removed from the lower end portion of the tubular member 1 as described, the spool S of cord is passed upwardly on said tubular member 1 until the inner face of the core 5' of the spool S of cord engages the circumferential face of the collar 5 which is mounted on the tubular member 1. The cap 3 is then replaced by moving it upwardly on the lower portion of the tubular member 1 with the protuberances 4 of said cap moving upwardly of the vertical portions of the slots 2, after which said cap is rotated to bring the protuberances of the cap into the horizontal portions of the slots.

When the spool S of cord is arranged in place with respect to the cord holder A it rests upon the annular flange 3' of the cap 3 and is in this manner mounted in place for use. The cord is then fed through the tubular member 1 and through the curved cord passageway 8 and an end portion of said cord hangs downwardly from the open end of the curved cord passageway 8 for convenient use, as is shown by broken lines in Fig. 2. When a package is to be tied, the cord is pulled out to provide a sufficient length of cord to tie the package and when the package has been tied the cord is drawn into the groove 11 so as to hold it in place and said cord is turned about the head 6 to bring a portion of said cord in contact with the cutting portion of the blade 10 so as to cut said cord, this being

shown at S' in Fig. 2. It will be noted that the head 6 is provided with an integral projection 12 which is located adjacent to the exposed portion 10' of the blade 10. The projection protects the cutting edge of the blade from damage and it also makes it less likely that a person's hand would come into contact with the exposed cutting portion of the blade.

I claim:

1. A holder for a spool of wrapping cord comprising a tubular member having an upper portion adapted for projection through an opening formed through a part of a structure by which the holder is supported, a fixed head at the upper end of said tubular member which is adapted for disposition above and in contact with said supporting structure and is provided with a cord passageway which communicates with the bore of said tubular member, a cap removably mounted on said tubular member adjacent to the lower end thereof and adapted to support a spool of cord on said tubular member beneath said supporting structure, and cutting means supported by said head and adapted for use in cutting said cord.

2. A holder for a spool of wrapping cord comprising a tubular member having an upper portion adapted for projection through an opening formed through a part of a structure by which the holder is supported, a fixed head at the upper end of said tubular member which is adapted for disposition above and in contact with said supporting structure and is provided with a cord passageway which communicates with the bore of said tubular member, a cap removably mounted on said tubular member adjacent to the lower end thereof and adapted to support a spool of cord on said tubular member beneath said supporting structure, cutting means supported by said head and adapted for use in cutting said cord, said cutting means comprising a blade disposed in a slot formed in said head and having an exposed cutting portion projected outwardly of said slot, and a protective projection on said head adjacent to said exposed portion of said cutting portion of said blade.

3. A holder for a spool of wrapping cord comprising a tubular member having an upper portion adapted for projection through an opening formed through a part of a structure by which the holder is supported, a fixed head at the upper end of said tubular member which is adapted for disposition above and in contact with said supporting structure and is provided with a cord passageway which communicates with the bore of said tubular member, a cap removably mounted on said tubular member adjacent to the lower end thereof and adapted to support a spool of cord on said tubular member beneath said supporting structure, and cutting means supported by said head and adapted for use in cutting said cord, said head being provided with a groove into which the cord is drawn for clamping said cord while it is being cut.

4. A holder for a spool of wrapping cord comprising a tubular member having an upper portion adapted for projection through an opening formed through a part of a structure by which the holder is supported, a fixed head at the upper end of said tubular member which is adapted for disposition above and in contact with said supporting structure and is provided with a cord passageway which communicates with the bore of said tubular member, a cap removably

mounted on said tubular member adjacent to the lower end thereof and adapted to support a spool of cord on said tubular member beneath said supporting structure, and cutting means supported by said head and adapted for use in cutting said cord, said head being provided with a groove that is located in opposed relation with respect to said cutting means into which the cord is drawn for clamping said cord while it is being cut.

5. A holder for a spool of wrapping cord comprising a tubular member having an upper portion adapted for projection through an opening formed through a part of a structure by which the holder is supported, a fixed head at the upper end of said tubular member which is adapted for disposition above and in contact with said supporting structure and is provided with a cord passageway which communicates with the bore of said tubular member, a cap removably mounted on said tubular member adjacent to the lower end having an annular flange adapted to support a spool of cord on said tubular member beneath said supporting structure, and cutting means supported by said head and adapted for use in cutting said cord.

6. A holder for a spool of wrapping cord comprising a tubular member having an upper portion adapted for projection through an opening formed through a part of a structure by which the holder is supported, a fixed head at the upper end of said tubular member which is adapted for disposition above and in contact with said supporting structure and is provided with a cord passageway which communicates with the bore of said tubular member, a cap removably mounted on said tubular member adjacent to the lower end thereof and adapted to support a spool of cord on said tubular member beneath said supporting structure, said tubular member being provided with opposed slots formed in the wall thereof and said cap having protuberances which extend into said slots for fixing said cap to said tubular member, and cutting means supported by said head and adapted for use in cutting said cord.

7. A holder for a spool of wrapping cord comprising a tubular member having an upper portion adapted for projection through an opening formed through a part of a structure by which the holder is supported, a fixed head at the upper end of said tubular member which is adapted for disposition above and in contact with said supporting structure and is provided with a cord passageway which communicates with the bore of said tubular member, a cap removably mounted on said tubular member adjacent to the lower end thereof and adapted to support a spool of cord on said tubular member beneath said supporting structure, said tubular member being provided with opposed inverted L-shaped slots formed in the wall thereof and said cap having protuberances which extend into said slots for fixing said cap to said tubular member.
